UNITED STATES PATENT OFFICE.

WILLIAM L. SANDAGE, OF INDIANAPOLIS, INDIANA, ASSIGNOR TO THE NATIONAL VOTING MACHINE COMPANY, OF INDIANAPOLIS, INDIANA, A CORPORATION OF INDIANA.

KEY CONSTRUCTION FOR REGISTERING-MACHINES.

No. 824,885.

Specification of Letters Patent.

Patented July 3, 1908.

Application filed December 30, 1904. Serial No. 238,994.

To all whom it may concern:

Be it known that I, WILLIAM L. SANDAGE, a citizen of the United States, residing at Indianapolis, in the county of Marion and State 5 of Indiana, have invented certain new and useful Improvements in Key Construction for Registering-Machines, of which the following is a specification.

This invention relates to the construction 10 of a key which may be employed singly or in series, and is particularly applicable to be used in all classes of machines that employ counters for adding purposes; and the object of the invention is to produce such a key that 15 will insure a positive operation of the counter when actuated by any suitable means for imparting movement thereto. A portion of a registering-machine embodying my said invention, wherein the advantages sought are 20 attained, will first be more particularly described in the annexed specification and the novel features thereof then pointed out in the claims.

Referring to the accompanying drawings, 25 which are made a part hereof, and on which similar numerals of reference indicate similar parts, Figure 1 is a fragmentary detail in vertical section of a registering-machine in which a plurality of keys are shown in operating position. In this view a part of the keys is shown in side elevation and a part in section. Fig. 2 is a fragmentary detail view in horizontal section of the registering-machine and shows in top plan view the mechanism for operating the key to actuate the 30 counter. Fig. 3 is a fragmentary detail view as seen when looking in the direction indicated by the arrows on the dotted line 3 3 in Fig. 2. Fig. 4 is a fragmentary detail view as seen 40 when looking in the direction indicated by the arrows on the dotted lines 4 4 in Fig. 3. Fig. 5 is an under side plan view of the construction shown in Fig. 3. Fig. 6 is a perspective view of one of the counters and 45 shows the stop-bar for stopping the counters at a given point when the latter are reset.

In the drawings, 1 constitutes the inner frame, which may be of any suitable shape to conform to the style of a machine desired 50 and supports the keys and counters.

Examining Figs. 1 and 2 of the drawings, it will be seen that I can arrange my keys and

counters in series, either in a vertical or horizontal direction, or both. As the several keys and their accompanying counters shown 55 throughout the several views of the drawings are all similarly constructed, a description of one is deemed sufficient for all.

The front portion of the key 5, hereinafter known as the "primary" member, is provided 60 with a knob 6, by which sufficient purchase can be obtained for manipulating the key. The primary member 5 of the key passes through the apertures 7 and 8 in the walls 9 and 10, secured to the frame of the register- 65 machine to form a guide for said member. The member 5 is also provided with a pin 12 for regulating the backward movement thereof. The rear end of the primary member 5 is provided with a slot 14, which slot receives 70 a tongue 15, formed on the rear portion of the key hereinafter known as the "secondary" member 16. The primary member 5 and secondary member 16 are pivotally secured together by means of the transverse pin 17. 75 The secondary member of the key is provided with an elongated slot 19 to receive a cam for returning the key to normal position, which will be hereinafter described. The extreme rear end of the key is greatly reduced in 80 width, so as to provide the narrow extending finger 20, which engages a ratchet-wheel formed integrally with the units-disk of the counter, so that the latter is operated when the key is returned to normal position. 85

Situated beneath the secondary member 16 of the key is the cam-shaft 25, which is mounted at right angles to the key and is supported in the frame 1 of the registering-machine. The cam-shaft 25 is provided with a 90 segmental disk 26, which is adjustably secured thereto and engages with the elongated slot 19 in the secondary member 16 of the key. The segmental disk 26 is provided with a cam-slot 30, and by means of a pin 31, 95 that passes transversely through said slot and the secondary member 16 of the key, the key and segmental disk are linked together.

When the segmental disk 26 is standing in normal position, which is indicated by the 100 full lines in Fig. 1 of the drawings, the key may be pulled forward and subsequently returned to normal position, if desired, as the elongated slot 19 in the secondary member

16 of the key and the cam-slot 30 in the segmental disk 26 permit this movement. When a key, however, is pulled forward, in which the cam-slot 30 permits the secondary member 16 to descend, as shown in the uppermost key in Fig. 1 of the drawings, and the movement is then reversed, the cam-slot 30 in the segmental disk 26 is cut on a radius that permits the key to return to normal position without permitting said secondary member 16 of the key to contact the ratchet-wheel and thus operate and change the total on the counter. This feature is of the highest importance, since it permits the return to normal of an inadvertently or fraudulently operated key without affecting the total on the counter. When, however, a key or any number of keys has been operated to meet one's satisfaction, it may be returned to normal, and with which same movement the counter is operated, by means of the segmental disk 26 and cam-slot 30. The distance and the arc through which the segmental disk 26 passes when returning the key from its operated to normal position is shown by means of the full and dotted lines in Fig. 1 of the drawings. The mechanism for operating the segmental disk 26 will now be described.

Examining Figs. 2 and 3 of the drawings, it will be seen that the registering-machine is provided with an exterior or outer frame 40 for housing the inner frame. Secured in a suitable manner to the outer frame 40, at one end of the machine, is the box 41, that forms a bearing for a revoluble drum 42 by means of a spindle 43 and nut 45. The drum 42 and other mechanism dependent thereon are operated by means of a handle 47, mounted on said drum.

A bar 50, provided with an integrally-formed ear 51, which is provided with a cam-slot 52, is slidably mounted on the under side of the inner frame 1 and is pivotally connected to the drum 42 by means of the pitman 55. A rack-bar 58 is slidably mounted on the side of the inner frame 1 and transversely with the sliding bar 50. The lower end of the rack-bar 58 is provided with a slot 59 (see Fig. 4) and carries the friction-roller 60, that engages with the cam-slot 52 in the ear 51 on the sliding bar 50. The sliding bar 50 is also provided with a slot 63, as shown in Fig. 5, in order to permit one of the extending sides of the rack-bar 58, formed by the slot 63, to pass. By means of this construction it will be seen that when the drum 42 is operated the sliding bar 50, ear 51, and the rack-bar 58, through the latter's connection with sliding bar 50, are operated. The direction taken by the parts is only conjecture unless a certain direction taken is described in the initial movement, and this will be hereinafter set forth.

Attention has previously been directed to

the cam-shaft 25, which carries the segmental disk 26 and which is supported in the inner frame 1 of the machine. Throughout the several views of the drawings it will be noted that where said shaft 25 passes through the side of the frame 1, having the rack-bar 58 slidably secured thereto, said shaft 25 is provided with a pinion 65, that is rigidly secured thereto. The pinion 65 meshes with the rack-bar 58, and obviously when said bar is actuated the shaft 25 and segmental disk 26 are rocked.

Accompanying the key and situated in the rear and in alignment therewith is the counter 70, which is composed of a series of disks all mounted on a counter-shaft 71, which is suitably supported in the inner frame 1 of the machine. A detail description of the counter employed in this device is deemed unnecessary, since it is similarly constructed as the one forming the subject-matter of Letters Patent of the United States No. 728,502, issued to me and bearing the date of May 19, 1903.

In order to clearly understand the initial movements of the parts of the registering-machine and the normal position of the keys and cams, an outline of the mode of operation seems desirable, which is as follows: To operate the registering device, the handle 47, mounted in the drum 42, is moved from its normal position shown by the full lines into the direction indicated by the arrow in Fig. 2. This movement of the drum 42 through the pitman 55 moves the sliding bar 50 away from said drum. This movement of the sliding bar causes the rack-bar 58 to descend through its connection with the cam-slot 52. The downward movement of the rack-bar 58 causes the pinion 65, that meshes therewith, to be moved from right to left, or in the direction indicated by the arrow above said pinion in Fig. 4. This movement of the pinion 65 rocks the cam-shaft 25 and segmental disk 26, that carries the cam-slot 30, moving them from the position indicated by the dotted lines to the position indicated by full lines in the uppermost key. (Shown in Fig. 1.) This movement of the segmental disk 26 does not affect the key, the latter remaining normal and in contact with the ratchet-wheel on the counter. After this movement of the segmental disk the key may be pulled out by means of the cam-slot 30, the latter permitting the secondary member 16 of the key to descend, as shown, in the uppermost key in Fig. 1. When that key has been pulled out that will subsequently actuate the counter in order to register the desired amount, the return of said key is effected by reversing the movement of the handle 47, which moves the sliding bar 50 toward it and by means of the cam-slot 52 the rack-bar 58 is moved upward. This reverse movement of the bar causes the

pinion 65 to rock the cam-shaft 25 from the position indicated by full lines to the position indicated by dotted lines in Fig. 1, and during which movement the segmental disk 5 raises the secondary member 16 of the key and simultaneously with the upward and backward movement thereof the key is passed through an arc by means of the cam-slot 30 in the segmental disk 26, that permits 10 it to engage the succeeding tooth in the ratchet-wheel, and thus actuate the counter. The parts now having been restored to normal, further registration requires a repetition of the above-described movements.

15 Having thus fully described my said invention, what I desire to secure by Letters Patent is—

1. A key for registering-machines, comprising a primary and secondary member 20 pivotally connected together, a counter, a key-operating means engaging the key, a cam-slot in the key-operating means which is cut so as to gradually increase its radius from the axis of the key-operating means and adapted 25 to permit the key to be moved to and from the counter without operating the latter when the former is in normal position but permitting the counter to be operated when actuated by said key-operating means, and 30 means in the key to engage the cam-slot in the key-operating means.

2. A key for registering-machines, comprising a primary and secondary member pivotally connected together, a counter, a 35 key-operating means engaging the key, a cam-slot in the key-operating means having terminals at the same radiiuses but having that portion of the slot between the terminals formed on greater radiiuses to permit the key 40 to be reseated without actuating the counter when said key-operating means stands in normal position.

3. A key for registering-machines, comprising a primary and secondary member 45 pivotally connected together, a counter, a key-operating means engaging the key, a cam-slot in the key-operating means, said slot permitting the key to be moved to and from the counter without operating the latter when 50 said operating means stands in normal position, but permitting the key to engage and operate the counter when the former is moved by the said operating means, and means for operating the key-operating means.

55 4. A key for registering-machines, comprising a primary and secondary member pivotally connected together, a counter, a key-actuator, means in one of the key-forming members to engage the said actuator, 60 a cam-slot in the key-actuator having terminals formed at an equal distance from the axis of the key-actuator, the course of the cam-slot between its terminals cut on a changing radii and situated more remotely

from the axis of the actuator than the said 65 terminals.

5. A key for registering-machines, comprising a primary and secondary member pivotally connected together, a counter, an independently-movable key-actuator, means 70 in one of the key-forming members to engage the said actuator, a cam-slot in the key-actuator having terminals formed at an equal distance from the axis of the key-actuator, the course of the cam-slot between its terminals cut on a changing radii and situated more remotely from the axis of the actuator than said terminals, and means in the slotted key-forming member for engaging the cam-slot in the key-actuator, so that after the key 75 is manipulated it will be returned to normal by operating the actuator.

6. A key for registering-machines, comprising a primary and secondary member, a tongue formed on one of said members, a 85 groove formed in the other member, a pin passing transversely through the key to pivotally connect the members together, a counter, an independently-movable key-actuator, a cam-slot in the key-actuator having terminals formed at an equal distance from the axis of the key-actuator but situated more nearly thereto than the main body of the 90 slot, means in the key to engage the cam-slot in the key-actuator, so that after the key is 95 manipulated it will be returned to normal by operating said actuator.

7. A key for registering-machines, comprising a plurality of members, means pivotally connecting the adjacent ends of the members together, a slot in one of the key members, a counter, an actuator mounted in relation with and engaging the slotted member of the key, a cam-slot in the actuator which is cut on an arc so that when it occupies one 100 position the key may be operated independently thereof without actuating the counter, and means carried by the actuator to move the key and actuate the counter.

8. A key for registering-machines, comprising a plurality of members, means for pivotally connecting the adjacent ends of the members together, a counter, a movable actuator having means for permitting the key to be moved independently of the actuator 115 without affecting the counter, and means carried by said actuator to move the key into engagement with and actuate the counter.

9. A key for registering-machines comprising a plurality of members pivotally connected together, a movable key-actuator for moving the key to normal and having a slot 120 to permit the key to be moved independently of said actuator, and means on the key to engage the slot in the key-actuator.

10. A key for registering-machines, comprising a primary and secondary member pivotally connected together, a counter, a

4
movable actuator, said actuator being provided with a curved slot with which the key engages so that when the latter is moved independently of said actuator the counter is not affected, but when said key is moved by said actuator the counter is operated.

In witness whereof I have hereunto set my

hand and seal, at Indianapolis, Indiana, this 27th day of December, A. D. 1904,

WILLIAM L. SANDAGE.
